ADJUSTABLE FASTENING DEVICE

Fred W. Andrews, Dover, Del., assignor to International Latex Corporation, Dover, Del., a corporation of Delaware

Application April 20, 1948, Serial No. 22,194

3 Claims. (Cl. 2—335)

1

This invention relates to adjustable fastening devices and more particularly to highly resilient adjustable garters. The invention is especially adapted for supporting hose from girdles or the like wearing apparel and is primarily intended for and serves a particularly useful purpose for use in conjunction with rubber latex or the like girdles.

While highly resilient or readily stretchable garters are desired for girdles and the like wearing apparel, it is particularly desirable that garters of this type be utilized in connection with relatively thin rubber latex or the like girdles, for example, such as disclosed in the patent to A. N. Spanel No. 2,360,736, granted October 17, 1944. Prior to the present invention no satisfactory way was known to provide for readily adjusting and maintaining the adjusted length of garters having stretch characteristics comparable to those of the material from which such rubber latex girdles were made.

For example, with the buckle arrangements heretofore known a garter comprising an adjustable length strap made of relatively thin rubber latex or the like sheet material would not maintain its desired adjusted length under repeated intermittent stress or stretch. This was due to the fact that such highly elastic and readily stretchable strap material is greatly reduced in its cross-sectional dimensions when elongated under stress and in the arrangements heretofore proposed for adjustable devices this reduction in cross-sectional area caused slipping of the strap with respect to its buckle or the like holding means. Another problem involved in solving this difficulty is due to the fact that any positive clamping action against the rubber strap or piercing of the same by a prong would be detrimental to the strap itself, causing it to break or tear.

An object of this invention is to provide a device having the desirable characteristics above stated while obviating the abovementioned difficulties.

A further object is to provide a device of the character described having relatively great elasticity in which the length may be readily adjusted and the adjusted length maintained without slipping.

Another object is to provide a highly elastic adjustable garter comprising strap means of rubber latex or the like sheet material.

A further object is to provide an adjustable buckle adapted to hold a relatively thin rubber latex strap in adjusted position without slipping.

2

when said strap is placed under repeated intermittent stress.

Further and more specific objects, features and advantages of the invention will more fully appear from the detailed description given below taken in connection with the accompanying drawings which form a part of this specification, and in which:

Fig. 1 is a front plan view of an embodiment of the invention;

Fig. 2 is a longitudinal sectional view taken on line 2—2 of Fig. 1;

Fig. 3 is a somewhat enlarged sectional view taken on line 3—3 of Fig. 2 showing further details of the buckle and attached strap portions;

Fig. 4 is a view similar to Fig. 2 but showing the strap in one stage of its adjusting position;

Fig. 5 is a front perspective view showing a further step in adjusting the strap length of the device of Fig. 1;

Fig. 6 is a front perspective view of the buckle of Fig. 1; and

Fig. 7 is a front perspective view of a modified form of buckle.

Referring to the drawings and more particularly to Fig. 1, a segment of a rubber latex girdle is designated as 1 having a dependent strap portion 2 from which it is desired to support the usual fastening means 3 for engagement with a hose. The fastening means 3 is provided with the usual button 3a and metal loop 3b. An adjustable garter strap 4, in the present embodiment made of rubber latex or the like sheet material having a thickness of the order of .025", has its lower end clamped to the fastening means 3 as by means of metal U-clamp 3c. The upper end of the strap 4 is held by an adjusting buckle 5 which is attached, as by means of the metal U-clamp 2c, to the strap portion 2.

The buckle 5 is made of relatively thin sheet metal, in the present embodiment of the order of .035" thickness, and has transversely extending slots 6 and 7 formed therein with the length of the slots extending crosswise of the buckle and being spaced apart lengthwise of the buckle to provide a first cross bar 8 therebetween. The slot 7 is spaced from the lower end of the buckle to provide a second cross bar 9 which has a lower edge defined by the lower end of the buckle. Similarly the slot 6 is spaced from the upper end of the buckle to provide an upper end bar 10 which serves as a convenient means to attach the buckle to the strap 2 from which it is to be permanently supported; being attached

thereto as by looping the strap 2 around the cross bar 10 with the free end 2b disposed over the main portion 2a and fastened in position by the U-clamp 2c previously described. Adjacent the lower end of the buckle a pair of flat jaws or fingers 11 and 12 extend from the respectively opposite edges of the body of the buckle and project forwardly and inwardly so as to overlie the lower edge of the cross bar 9 in parallelism therewith. The jaws 11 and 12 are disposed in transverse alignment overlying the adjacent face of the buckle and spaced upwardly therefrom to provide a transversely extending throat 13; the inner ends of the fingers 11 and 12 are spaced apart to form a mouth 14.

The upper slot 6 preferably is somewhat longer than the normal unstretched width of the strap 4 and is of such a width as to readily accommodate the strap 2 and its clamp 2c together with two thicknesses of the strap 4 passing through said slot, for the purposes to be more particularly pointed out below. The slot 7 is formed on an arc throughout its length which is slightly less than the normal or unstretched width of the strap 4, while the width of the slot 7 is somewhat greater than the normal thickness of the strap, preferably about twice the thickness of the strap in its normal or unstretched condition. From this it will be seen that the slot 7 restrictively engages the strap by causing it to be bowed so that the upper surface of the strap is frictionally engaged against the upper edge of the slot 7. As far as the function of the device is concerned this slot could be approximately the same length as the width of the strap and of a width equal to the thickness of the strap but it has been found difficult to make slots of such a narrow width in mass production. The throat 13 is of a length in a transverse direction substantially equal to the width of the strap 4 in its normal or unstretched condition and the width of the throat 13 is equal or slightly less than three times the thickness of the strap 4 in its normal condition. The mouth 14, i. e., the space between the inner ends of the jaws 11-12, is preferably as great as the width of the slot 6 and no greater than one-third of the length of the throat 13. The importance of these various dimensions and their significance in the successful operation of the device will be better understood from the relationship of the buckle and strap now to be described.

The main part of the strap, designated 4a, passes upwardly through the throat 13 closely adjacent to the inner faces of the jaws 11-12 (Fig. 2) thence rearwardly through the wider slot 6 and downwardly around the lower edge of the second bar 9, upwardly through the throat 13 against the upper face of the bar 9 thence abruptly rearwardly through the narrow slot 7, upwardly beneath the first or outer turn of the strap over the rear face of the first bar 8, abruptly forwardly through the wider slot 6 thence downwardly over the front face of the bar 8 and thence downwardly through the throat 13 intermediate the strap portions previously described. The manner of placing the strap in position in the buckle will best be understood by reference to Fig. 4 from which it will be seen that the strap is passed from front to back through the wider slot 6 then downwardly behind the buckle, upwardly through the throat 13, rearwardly through the narrow slot 7, upwardly over the first bar 8 then outwardly beneath itself and through the wider slot

6. The main strap portion 4a and the free or tail strap portion 4b in superimposed position are then inserted through the mouth 14 beneath one of the jaws, such as 12 (Fig. 5) and the strap portions 4a and 4b are pulled to the right until the opposite or left hand edges are over the mouth 14 which permits them to be inserted beneath the opposite jaw 11. When it is desired to adjust the length of the strap the reverse performance is repeated to remove the superimposed layers 4a and 4b from the jaws 11-12 to the position shown in Fig. 4 so that either strap portion 4a or 4b may be pulled outwardly until the proper adjustment is made, at which time the overlying strap portions may again be inserted beneath the jaws or fingers 11-12. It has been found that in addition to the relatively narrow width of the slot 7 with respect to the slot 6, that the three thicknesses of strap passing through the throat 13 should be held flatly and closely one against the other and against the front face of the body of the buckle and against the inner faces of the jaws 11-12 so that the three thicknesses are snugly engaged in face-to-face relation within the throat 13 when the strap is in its normal or untensioned condition. I have found that with the parts as above shown and described the garter may be placed under relatively great tension intermittently and repeatedly without causing any slipping of the adjusted position. From the foregoing it will be understood that the lateral extent or length of the throat 13 and the opening of the mouth 14 should be such that any sidewise pull of the strap 4 in normal use will not tend to dislodge the strap from the throat 13.

With reference to Fig. 2, it will be noted that the upper portion of the buckle, forming in the present embodiment the cross bar 10, is offset from the plane of the main body of the buckle a sufficient distance upwardly so that it is disposed over the throat 13, thereby placing the adjusted strap 4 in substantial vertical alignment with the supporting strap 2. This provides an optimum position of alignment.

In Fig. 7 I have shown a modified form of buckle in which the respectively corresponding parts are designated with the same numerals referring to the parts of Fig. 6 but with the prime suffix added. The difference between this modification and the embodiment of Fig. 6 resides in the utilization of a straight slot 7' instead of the curved slot 7 of Fig. 6; the straight slot 7' being of a length substantially equal to the width of the strap 4 in normal condition and of a width equal to or slightly less than the thickness of the strap 4 in normal condition. The lower edge of slot 7' is preferably spaced from the lower edge of the buckle a distance substantially equal to the width of the fingers or jaws 11'-12'. With this arrangement of the slot 7' the over-all height of the buckle may be less than the height of the buckle shown in Fig. 6. As above explained, this modified form of buckle functions satisfactorily but is more difficult to make in mass production due to the difficulties in forming a slot so positioned and of such a narrow width.

Having thus described my invention with particularity, with reference to the preferred embodiment of the same, and having referred to certain modifications thereof, it will be obvious to those skilled in the art, after understanding my invention, that other changes and modifications may be made therein without departing

from the spirit or scope of my invention and I aim in the appended claims to cover such changes and modifications as are within the scope of the invention.

What I claim is:

1. An adjustable fastening device comprising a buckle having an end adapted to be attached to a supporting strap-like member and having a pair of transverse slots, one of said slots being of narrower width than the other, the narrower slot being disposed in spaced relation with respect to the wider slot to provide an intervening first bar and being spaced from the opposite end of said buckle to provide a second bar, a pair of jaws extending from respectively opposite sides of said body and disposed over said second bar in spaced relation thereto to provide a throat and having their inwardly directed ends spaced apart to provide a mouth, and a strap whose length is to be adjusted, said strap being looped about said second bar with a tail portion passing upwardly through said throat thence rearwardly through said narrow slot and a main portion passing upwardly over the rear of said second bar and both portions in superimposed relation passing over the rear face of said first bar thence forwardly through said wide slot and downwardly over the front face of said first bar and over the portion of said tail portion lying over said second bar and outwardly through said throat, said main portion of said strap extending beyond said tail portion and the lower end of said main portion being adapted to be connected to an article of wearing apparel.

2. An adjustable fastening device for supporting hose from girdles comprising a buckle having a dependent strap, said device having an upper end bar for attachment to said strap and a pair of spaced transverse slots providing therebetween a first cross bar, one of said slots being of narrower width than the other, said narrower slot being spaced from the opposite end of said buckle to provide a second cross bar, a pair of jaws extending from respectively opposite sides of said body and disposed over said second cross bar in spaced relation thereto to provide a throat and having their inwardly directed ends spaced apart to provide a mouth, and a strap of latex rubber or the like highly elastic material of a thickness of the order of .025" whose length is to be adjusted, said strap being looped about said second cross bar with one portion thereof passing upwardly through said throat thence rearwardly through said narrow slot and with the other portion passing upwardly over the rear of said second cross bar and both portions in superimposed relation passing over the rear face of said first cross bar thence forwardly through said wide slot and downwardly over the front face of said first cross bar and over the portion of said one portion of said strap lying over said second cross bar and outwardly through said throat, said other portion

of said strap extending downwardly beyond said one portion and having its lower end attached to a fastening means for engagement with a hose and said narrow slot being curved in the direction of its length and being of a width approximately twice the thickness of and a length less than the respective normal thickness and width of said strap, and said throat having a width of the order of three times said normal strap thickness and a mouth extending less than one-third the throat width, whereby said strap portions are firmly locked in the desired and readily adjusted position relative to said buckle.

3. An adjustable garter for rubber latex girdles having a dependent elastic strap, said garter comprising a buckle having at its upper end means adapted to be attached to said strap, a second cross bar at its lower end and a first cross bar spaced from the second cross bar to provide a relatively narrow slot, said buckle also having a pair of oppositely disposed fingers extending forwardly from respectively opposite sides of said buckle and thence inwardly over and in spaced relation to the front face of said second cross bar and toward each other with their inner ends spaced apart to provide a mouth, and a relatively thin sheet rubber strap looped about said second cross bar with the two strap portions passing upwardly, one of said portions passing over the front and top of said second cross bar beneath said fingers thence rearwardly through said narrow slot, the other of said strap portions passing over the rear of said second cross bar upwardly to overlie said rearwardly disposed one portion and both of said portions in superimposed surface contacting relationship passing upwardly over the rear face of said first cross bar, thence forwardly over the top of said first cross bar and downwardly over the front face of said first cross bar and thence over said one strap portion overlying said second cross bar and beneath said fingers, the three plies of said strap being in intimate surface contact with each other and closely confined between said second cross bar and fingers and said other portion of said strap extending downwardly beyond said one portion and having its lower end attached to a fastening means for engagement with a hose.

FRED W. ANDREWS.
